SYSTEM OF CONTROL FOR ELECTRIC MOTORS.

1,027,846.

Specification of Letters Patent.

Patented May 28, 1912.

Application filed October 8, 1908. Serial No. 456,741.

To all whom it may concern:

Be it known that I, ALBERT J. HORTON, a citizen of the United States, residing at White Plains, in the county of Westchester 5 and State of New York, have invented new and useful Improvements in Systems of Control for Electric Motors, of which the following is a full, clear, concise, and exact description, reference being had to the accompanying drawing, forming a part of this 10 specification.

My invention relates to improvements in systems of control for electric motors, and more particularly to means for causing a 15 motor to operate either at normal speed or slow speed. Such systems of control are commonly employed in connection with printing presses where it is desired to operate the press as slow speed for "inching."

One object of my invention is to provide 20 means whereby the motor may be caused to run at normal speed by operating the controlling arm of a rheostat or at slow speed, from points about the press or other machine, when the rheostat arm is in a predetermined position, said rheostat arm having a "full off" position for rendering closure of the motor circuit impossible.

Other objects and advantages will be hereinafter set forth.

For the purpose of more fully disclosing my invention I have diagrammatically illustrated, in the accompanying drawing, a system of motor control embodying one form 35 thereof. Of course, other systems embodying my invention may be developed.

The system which I have shown for the purpose of illustration, includes a main switch 1, carried by the plunger 2 of a solenoid 3. The main switch is provided with main contacts 4 and 5 adapted to engage stationary contacts 6 and 7, respectively, and arcing contacts 8 and 9 which are adapted to engage stationary arcing contacts 10 and 11, respectively. When the main switch is open the contacts 8 and 9 engage stationary contacts 12 and 13. At its upper end, the plunger 2 of the solenoid 3, carries a tail rod 3^a upon which is loosely mounted a 45 contact disk 14, adapted to bridge contacts 15 and 16 when the main switch is open. The tail rod 3^a carries a collar 3^b, so adjusted thereon as to engage and raise the disk 14 from the contacts 15 and 16 when the core 3 55 has been sufficiently raised to close the main

switch. I also provide a rheostat having a movable controlling arm 17 which is provided with an operating handle 18. The arm 17 carries brushes 19 and 20. The brush 20 is adapted to be moved over a series 60 of contacts 21, while the brush 19 is adapted to be moved over contacts 22, 23 and 24 and contact segment 25. The contacts 22, 23 and 24 and the contact segment 25 are so arranged that when the arm 17 is in its 65 initial position, the brush 19 engages contact 22. When brush 20 engages the second of the series of contacts 21, the brush 19 engages contact 23 and when the brush 20 engages the third of the series of contacts 70 21, the brush 19 engages the contact segment 25 and contact 24. During the continued movement of the arm 17 to the right the brush 19 engages the contact segment 25.

The motor illustrated is of the shunt-wound type being provided with an armature *a* and shunt-field winding *f*. Of course, the motor may be of any preferred type. One terminal of the armature *a* is connected by conductor 26 to main line 27. The opposite terminal of the motor armature is connected by conductor 29 to contact 6. Contact 7 is connected by conductor 30 to the last of the series of contacts 21. All but the first three of the series of contacts 21 are 85 connected to an armature resistance 31. The first of the series of contacts 21 is dead, while the second, third and fourth are electrically connected. The arm 17 is connected by conductor 32 to main line 28. One terminal of the shunt-field winding *f* is connected by conductor 33 to conductor 32, while the opposite terminal of said winding is connected by conductor 34 to conductor 26. Contact 13 is connected by conductor 35 90 to conductor 29. Contact 12 is connected by conductor 36, through a resistance 37, to conductor 26. Contact 15 is connected by conductor 38 to contact 24. Contact segment 25 is connected by conductor 39, through a 95 resistance 40, to contact 16. Contact 16 is connected by conductors 41 and 42 through push-buttons 43, by conductor 44, to one terminal of the solenoid winding 3. The opposite terminal of the winding 3 is connected by conductor 45 to main line 27. Contact 23 is connected by conductors 46 and 47 to contact 48. The push-buttons 43 tend to stand in the position shown, but are adapted to be moved into engagement with the contacts 48. 100 105 110

While I have shown only two push-buttons it should be understood that any number of the same may be provided, and may be placed in any desirable location.

5 I shall now describe the operation of this system.

Assuming that the arm 17 of the rheostat is in its extreme left-hand position, the brush 20, carried thereby, will engage the 10 first of the series of contacts 21, while the brush 19 will engage contact 22. Inasmuch as both of these contacts are dead the motor circuit will be open. Assuming now that the arm 17 be moved so that the brush 20, carried thereby, will engage the second of the series of contacts 21 and the brush 19 will engage contact 23, circuit may be closed through the operating winding of the main switch by moving either of the push-buttons 43 into engagement with one of the contacts 48. The circuit for the winding 3 may then be traced from main line 28, by conductor 32, through the arm 17 and brush 19 to contact 23, thence by conductors 46 and 47 to one of the contacts 48, through one of the push-buttons 43, by conductor 44, through the winding 3 and by conductor 45 to main line 27. As soon as the circuit of the winding 3 is closed, said winding will 25 respond and close the main switch. The motor circuit may then be traced, as already described, to the arm 17 by brush 20 to the second of the series of contacts 21, through all of the resistance 31, by conductor 27 and 30 to contact 7, across main switch 1 to contact 6, by conductor 29 through the armature α , and by conductor 26 to main line 27. Inasmuch as the shunt-field winding f is connected directly across the main line, the 35 motor is started under full field strength. The circuit for the shunt-field winding f may be traced from main line 28, by conductor 33, through the winding f , by conductors 34 and 26, to main line 27. It will 40 thus be seen that as long as the push-button 43 is held in engagement with contact 48, the motor will operate at a slow speed with all of the resistance 31 in circuit. When it is desired to stop the motor it is only necessary to release the push-button 43, whereupon the circuit of the winding 3 will be 45 opened, thus permitting the main switch to open. With the arm 17 in the position just described, it will be apparent that the motor may be started and stopped any number of times by the operation of either of the push-buttons 43. As before stated, any number of push-buttons may be provided and the same may be located in any convenient position. Assuming now that the 50 arm 1 be moved farther to the right so that the brush 19 will engage contact segment 25 and contact 24, and assuming that the push-buttons 43 are in the position 55 shown, the circuit of the winding 3 will be

closed. This circuit may be traced from brush 19 to contact 24, by conductor 38 to contact 15, across contact plate 14 to contact 16, by conductors 41 and 42, through the push-buttons 43, by conductor 44, through 70 the winding 3, and thence by conductor 45 to main line 27. The winding 3 will then again respond and close the main switch 1. As soon as the main switch 1 is closed, the armature circuit will again be completed 75 and may be traced, as already described. As soon as the winding 3 responds to close the main switch the contact plate 14 is raised from the contacts 15 and 16. This results in opening the circuit for the winding 3 just described, but upon the opening of this circuit, a maintaining circuit is established. This circuit may be traced from brush 19 to contact segment 25, by conductor 39, through resistance 40 to contact 80 16, and thence through the winding 3, as already traced. This maintaining circuit is maintained closed during the continued movement of the arm 17 to the right. The resistance 40 in the maintaining circuit cuts 85 down the flow of current through the winding 3 to an amount just sufficient to cause said winding to maintain the main switch closed, but prevents said winding from reclosing said switch until after the removal of 90 the resistance 40. As will be hereinafter explained, the resistance 40 is only short-circuited when the arm 17 is in such a position as to insert all of the resistance 31 in the armature circuit. Assuming now that 95 the arm 17 is moved farther to the right it will gradually remove the starting resistance 31 from the armature circuit, and when it reaches its extreme right-hand position, will remove all of said resistance from 100 105 circuit and cause the motor to operate at normal speed. After the motor has been brought up to normal speed it may be stopped by returning the arm 17 to its initial position, or by operating either of the 110 push-buttons 43. By operating either of the push-buttons 43 the circuit of the solenoid winding 3 is opened, thus permitting the main switch to open. When the main switch opens, the contacts 8 and 9, carried 115 thereby, engage contacts 12 and 13. This establishes a dynamic breaking circuit across the terminals of the motor armature. This circuit may be traced from one terminal 120 of the motor armature by conductors 29 and 35 to contact 13, across the main switch 1 to contact 12, by conductor 36, through resistance 37, to the opposite terminal of the armature. The establishment of this circuit quickly brings the motor to a state of 125 rest. Assuming now that the motor circuit has been opened without returning the arm 17 to initial position, the main switch cannot be again closed until said arm has been moved to the left to bring the brush 19 into 130 135

engagement with the contact 24 or the contact 23. As already stated, the contacts 23 and 24 are so located that the arm 17 must be moved to insert all of the resistance 31 before the brush 19 engages the same.

Having thus described my invention, what I claim as new and desire to secure by Letters Patent, is:

1. In a motor controller, in combination, 10 an automatic main switch, a resistance varying element adapted to be moved to cause operation of said main switch, and auxiliary means for causing operation of said main switch when said element is in a predetermined position, said element, when in initial position, being adapted to render said auxiliary means ineffective to cause the operation of said main switch.

2. In a controller for electric motors, in 20 combination, an electroresponsive main switch for controlling the motor circuit, a rheostat having a movable element adapted to be moved to energize said main switch, and auxiliary controlling means adapted to be operated to energize said main switch when said rheostat element is in a predetermined position, said rheostat element, when in initial position, being adapted to render said auxiliary means ineffective to 30 energize said main switch.

3. In a controller for electric motors, in combination, an electroresponsive main switch for controlling the motor circuit, a rheostat having a movable element adapted 35 to be moved to energize said main switch, and auxiliary controlling means adapted to be operated to energize said main switch when said rheostat element is in a predetermined position, said rheostat element, when in initial position, and when moved beyond a predetermined point, being adapted to render said auxiliary means ineffective to energize said main switch.

4. In a controller for electric motors, in 45 combination, an electroresponsive main switch, a rheostat having a movable element adapted to be operated, to cause said main switch to respond, and auxiliary means adapted to be operated, when said rheostat element is in a predetermined position to cause said main switch to respond, said rheostat element, when in initial position and when moved beyond a predetermined point, being adapted to render said auxiliary means ineffective to energize said main switch, said auxiliary means being adapted, at all times, to be operated to deenergize said main switch.

5. In a motor controller, in combination, 60 an electroresponsive main switch, one or more controlling switches therefor, and a rheostat having a movable element adapted, when in one position, to establish circuit connections whereby any one of said controlling switches may be operated to energize said

main switch, said rheostat element being movable to another position to energize said main switch without operation of said controlling switches and adapted, when in initial position, to render said controlling 70 switches ineffective to energize said main switch.

6. In a controller for electric motors, in combination, a rheostat having a movable element, an electroresponsive main switch 75 adapted to be energized by said rheostat element when in a predetermined position, one or more controlling switches adapted to be actuated to energize said main switch when said controlling element is in another 80 position, said element, when in initial position, being adapted to render said main switch ineffective to close the motor circuit.

7. In a controller for electric motors, in combination, an electroresponsive main 85 switch, a rheostat having a controlling element movable to energize said main switch, one or more auxiliary switches and circuit connections whereby said auxiliary switch, or switches, may be operated to energize said 90 main switch when said rheostat element is in a predetermined position, said rheostat element, when in initial position, being adapted to interrupt the motor circuit.

8. In a controller for electric motors, in 95 combination, an electroresponsive main switch, one or more controlling switches, a rheostat having a movable element adapted to establish circuit connections whereby said controlling switch, or switches, may be 100 operated to energize said main switch, said rheostat element being adapted, when in initial position and when moved beyond a predetermined point, to interrupt said circuit connections and a maintaining circuit for 105 said electroresponsive switch controlled by said rheostat element.

9. In a controller for electric motors, in combination, an electroresponsive main 110 switch, one or more controlling switches, and a rheostat having a movable element adapted to establish circuit connections whereby said controlling switch, or switches, may be 115 operated to energize said main switch, said rheostat element being movable to energize said main switch without operation of said controlling switch, or switches, and being adapted, when in initial position and when moved beyond a predetermined point, to render said auxiliary 120 switch, or switches, ineffective to energize said main switch.

10. In a motor controller, the combination with an electromagnetically operated main switch, of a rheostat having a movable member adapted, in one position, to interrupt the motor circuit, a plurality of switches, each adapted to be actuated to cause the energization of the operating winding of 125 said main switch when said movable mem- 130

ber is in another position, said movable member, when in a third position, being adapted to cause the energization of the operating winding of said main switch.

- 5 11. In a motor controller, the combination with an electromagnetically operated main switch, of a rheostat having a controlling arm adapted, when in one position, to interrupt the motor circuit, and a plurality of switches tending to stand in a certain position, each of said last mentioned switches being adapted to be actuated to cause the energization of the operating winding of said main switch when said rheostat arm is in another position, said rheostat arm, when in a third position, being adapted to cause the energization of the operating winding of said main switch, and circuit connections whereby said last mentioned switches 15 may be actuated to cause the deenergization of the operating winding of said main switch when said rheostat arm is in said third position.
- 10 12. In a motor controller, the combination

with an electromagnetically operated main switch, of a rheostat having a movable arm adapted, when in one position, to interrupt the motor circuit, and a plurality of switches, each adapted to be actuated to close the circuit of the operating winding of said main switch when said rheostat arm is in another position, said last mentioned switches tending to move to a position to cause the deenergization of the operating winding of said main switch, said rheostat arm, when in a third position, being adapted to close the circuit of the operating winding of said main switch, said last mentioned switches being included in circuit with the operating winding of said main switch. 40

In witness whereof, I have hereunto subscribed my name in the presence of two witnesses.

ALBERT J. HORTON.
